UNITED STATES PATENT OFFICE.

LILLIAN GRANVILLE WALKER, OF BOSTON, MASSACHUSETTS.

DESIGN FOR A CORSET.

SPECIFICATION forming part of Design No. 33,719, dated December 11, 1900.

Application filed April 4, 1900. Serial No. 11,544. Term of patent 14 years.

To all whom it may concern:

Be it known that I, LILLIAN GRANVILLE WALKER, a citizen of the United States, residing at Boston, in the county of Suffolk and State of Massachusetts, have invented and produced a new and original Design for Corsets, of which the following is a specification, reference being had to the accompanying drawings, forming part thereof, in which—

Figure 1 represents a perspective view of a corset embodying my new design, and Fig. 2 is an edge view of the front edge of the corset.

As shown in the drawings, the leading or material feature of my design consists of the configuration or shape of the front edge *a*, waist edge *b*, bust edge *c*, back edge *d*, and seams *d'*. The front edge *a* is convex-shaped and meets the waist edge *b* at the point *e*. The waist edge meets the back edge *d* at *f*. The back edge *d* is provided with the reentrant openings *b'* and *b''* and with the convex-shaped por-

tions *b³*, *b⁴*, and *b⁵*. The back edge *d* meets the bust edge *c* at *g*, the bust edge *c* meeting the front edge *a* at *h* and being provided with the reentrant opening *c'* and the convex-shaped portions *c²* and *c³*. The seams *d'* run in an oblique direction from the bust edge *c* to the waist edge *b*, substantially as shown in the drawings.

Having described my invention, what I claim as new, and desire to secure by Letters Patent, is—

The design for a corset, as herein shown and described.

In testimony whereof I have signed my name to this specification, in the presence of two subscribing witnesses, on this 8th day of January, A. D. 1900.

LILLIAN GRANVILLE WALKER.
